CARBURETOR

William C. Rayfield, Detroit, Mich., assignor to
Detroit Lubricator Company, Detroit, Mich., a
corporation of Michigan

Application February 7, 1934, Serial No. 710,068

17 Claims. (Cl. 261—34)

My invention relates to new and useful improvements in carburetors, and more particularly to a carburetor for supplying a mixture of fuel and air to an internal combustion engine.

5 An object of my invention is to provide a carburetor which will operate efficiently to supply the desired ratio of fuel to air in accordance with the needs of the engine supplied thereby.

Another object is to provide a carburetor having provision for increasing the ratio of fuel to air at the will of the operator for starting and warming-up operations of the engine.

Another object is to provide means for automatically increasing the volume of the fuel mixture supplied to the engine during the starting and warming-up periods of operation.

Another object is to provide a carburetor having means to increase the ratio of fuel to air for engine acceleration and for high power demands of the engine.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated a preferred embodiment of my invention, in which drawings—

30 Figure 1 is a view in side elevation of the carburetor of my invention;

Fig. 2 is a top plan view thereof;

Fig. 3 is a view in section on the line 3-3 of Fig. 1;

35 Fig. 4 is a view in section on the line 4-4 of Fig. 3;

Fig. 5 is a detail view, partly in section, on the line 5—5 of Fig. 2;
Fig. 6 is a detail view in section on the line 6—6 of Fig. 5;

Fig. 7 is a detail view in section on the line 7-7 of Fig. 2;

Fig. 8 is a detail view in section on the line 8-8 of Fig. 5, and Fig. 9 is a diagrammatic view showing the

Fig. 9 is a diagrammatic view showing the ports and passageways and the interrelation of the parts of the carburetor.

50 Referring to the drawings by characters of reference, 1 designates generally the hollow body member or casing of a carburetor, shown as of the downdraft type, and includes an air inlet member 2, a mixing chamber member 3 and a throttle body member 4. These members are preferably secured together and mounted in vertical alignment to provide an open-ended, vertically extending, main mixture passageway therethrough, including an air inlet 5, a mixing chamber 6 and a mixture outlet 7. The throttle body member 4, which includes the outlet 7 and part of chamber 6, is preferably substantially

cylindrical, having a laterally projecting, surrounding flange 8 at its lower end provided with stud or bolt receiving apertures 9 by which the carburetor may be secured to the engine inlet manifold or block, not shown. At its upper end the member 4 has a lateral surrounding flange 10 on which is seated the lower end of the mixing chamber member 3 which is also provided with a lateral surrounding flange 11. The members 3 and 4 are tightly clamped together by screws or bolts 12 extending through the flange 10 and threaded into the flange 11. The passageway through the mixing chamber member 3 is preferably substantially rectangular in plan for cooperation with pivoted suction operated means, to be described. At its upper end, the member 3 is provided with a lateral surrounding flange 13 which receives a lateral surrounding flange 14 on the lower end of the air inlet member 2. The flanges 13 and 14 are rigidly clamped together by bolts, or the like, 15 to secure the members 2 and 3 tightly together. The joints between the flanges 10 and 11 and between the flanges 13 and 14 are preferably provided with gaskets to insure a tight joint and prevent leakage. The air inlet member 2 is preferably provided with downward and inward tapering, internal, side walls converging in the direction of air flow to increase the velocity of air flowing through the air inlet 5. Positioned centrally within the inlet 5 and extending longitudinally thereof, there is a dashpot casing or housing 17 which is hollow and open at its top and bottom ends. The casing 17 is held in fixed position in the inlet 5 by oppositely extending supporting members or arm 18 which are preferably streamlined, see Fig. 3, and which extend across into engagement with opposite portions of the inside face of the side wall of the member 2 to which the arms 18 are rigidly joined. The casing 17, the member 2, and the supporting members 18 are preferably integrally formed as by die casting, or the like. The upper open end of the casing 17 is internally screw-threaded to receive a hollow closure member or plug 19 having a lateral, circumferential flange adapted to clamp a gasket against the top end face of casing 17. Supported in the plug member 19 and projecting freely through an aperture in the inner end wall thereof into casing 17 there is a fuel metering pin 20. The pin 20 is preferably in the form of a tapered needle valve and is universally supported, as at 21, in an adjustable stem member 22. The member 22 has screw-threaded engagement, as at 23, with the internal wall of the plug member 19 so that rotation of the member 22 will adjust the valve or pin 20 longitudinally. The member 19 is provided above its internally threaded portion with a packing recess 24 surrounding the member 22. Within the recess 24 there is packing material 25 held under compression by a coil 26.

spring 26 to prevent leakage around the stem 22. The spring 26 is held under compression and within the recess 24 by an annular end plate or washer 27 which surrounds stem 22 and which 5 closes the top open end of the recess 24. The washer 27 is preferably rigidly fixed in position by forcing the metal of the member 19 over thereon, as at 28. Within the casing 17 there is a dash-pot piston 30 having a hollow open-ended stem 31 which projects out of the lower open end of the casing 17. The stem 31 is rigid with piston 30 and serves as a nozzle tube having its bore or passageway 32 opening, as at 32^a, through the 10 piston 30 to provide a fuel supply port. The metering valve 20 extends into the inlet port 32^a and cooperates therewith to meter fuel flow through the passageway 32. The lower end portion of the casing 17 is of reduced internal diameter, as at 33, 15 piston 30 to provide a guideway in which the nozzle tube 31 has a free sliding fit, thereby closing the lower end of the chamber 29 and also providing an upward facing, annular shoulder 34 surrounding the tube 31. Positioned within the chamber 29 and held 20 under compression between the shoulder 34 and the piston 30, there is a helical coil spring 35 which surrounds the tube 31 and which normally tends 25 to move the piston 30 relative to the valve 20 to reduce the effective flow area of the annular inlet port 32^a. Through the stem 31 substantially 30 in the plane of its juncture with the piston 30, there is a small vent or bleed port 35^a preferably of about 0.028 inch diameter and which serves to relieve the dash-pot chamber of fuel vapor 35 or gas bubbles. When the engine is hot, the liquid fuel in the dash-pot chamber 29 will boil and unless some venting means such as port 35^a is provided, the gas bubbles will collect in the bore of casing 17 above the piston. These bubbles if permitted to so collect will obstruct the 40 annular orifice around pin 20 and intermittently resist the free passage of liquid fuel through port 32^a causing uneven feeding of fuel to bore 32 and surging of the engine. The port 35^a permits the bubbles to by-pass the port 32^a and 45 pass directly from the dash-pot chamber into the bore 32. Secured on the projecting end of the stem or tube 31 there is a nozzle member 36 having a sleeve portion 37 which surrounds 50 and receives the reduced lower end portion of the casing 17. Within the outlet end of the passageway 32, there is a calibrated plug 38 having a marginal flange which overlies the end of the tube 31 so that the plug 38 is held in position by 55 the nozzle member 36. The plug member 38 defines the main nozzle jet and determines the maximum flow area of the passageway 32. The nozzle member 36 is preferably provided with a plurality of intersecting radial slots 39 which serve to diffuse and break up the fuel discharged from the nozzle. Supported on the flange 13 or upper end wall of member 3 and extending across the main passageway through casing 1, there are substantially parallel bearing shafts 40 which are positioned 60 adjacent one pair of the opposite side walls of member 3 and have their opposite ends confined within downward open recesses 41 formed in the underface of the flange 14, see Fig. 3. Journaled on the shafts 40 for downward 65 swinging movement, there are air valve or vane members 42 which converge downward into engaging relation with each other, as at 42^a, within the member 3 to substantially close the main passageway through the casing 1. The members 76 42 are preferably substantially rectangular so

that they cooperate with the rectangular mixing chamber 6 to effectively control flow through the main passageway. The side edges of the members 42 transverse to shafts 40 are only sufficiently spaced from their adjacent walls so that they 5 may have free swinging movement. Projecting from the members 42 there are operating arms or fingers 43 which extend toward the casing 17 and which terminate within a circumferential groove 44 formed in the nozzle member sleeve 10 portion 37. The fingers 43 operatively connect the suction operated valve members 42 and the dash-pot piston 30 so that the dash-pot serves to control the opening movement of the valve members 42. It will also be noted that the valve 15 members 42 act through the fingers 43 to regulate the annular fuel orifice around the metering pin 20 by movement of the piston 30 relative thereto. Cooperable with the vane members 42 there are a pair of deflector members 45 which 20 converge toward each other and project from the opposite side walls of the member 3 between and within the angle formed by the vane members 42 so as to form a continuation of the converging side walls of the air inlet member 2 to 25 direct the incoming air toward the nozzle outlet. The underside edges 46, see Fig. 2, of the members 45 converge downward at an angle equal to the angle between the members 42 which when closed substantially seat thereon at their 30 side edges to further effectively close the main passageway from the inlet 5. Through the engaging edges of the vane members 42, there is a substantially cylindrical aperture 47 which receives the nozzle member 36, the aperture being of 35 slightly larger diameter than the diameter of the member 36 to provide for primary air flow when the vane members 42 are in closed position. Flow through the main passageway and discharge from the outlet 7 is controlled by a suitable control means 48 such as a throttle valve of the butterfly type secured to the shaft 49 journaled in the side walls of the member 4 and having one end projecting therethrough to receive an operating lever 50. Rigid with the lever 50 40 there is an adjustable stop member 51 cooperable with a fixed abutment or stop 52 carried externally by the member 4 to limit closing movement of the throttle valve 48. The lever 50 is preferably provided with a fixed stop portion 53, also cooperable with the stop member 52 to limit opening movement of the throttle valve 48 so that the throttle valve will not be rotated beyond full 50 open position.

The mixing chamber member 3 serves to support a fuel reservoir or constant level chamber 54 which is preferably formed integrally therewith as by die casting. The chamber 54 is positioned at one side of the throttle body member 4 and preferably has a wall portion 55 in common with 60 the chamber 6. The chamber 54 is provided with a fuel inlet passage 56 which leads into a cup 57 having an overflow edge 58 for admission of fuel to the main reservoir 59. Within the cup 57 there is a valve casing 60 containing a valve port 61 intermediate the ends of a passageway 62 through the casing 60. The passageway 62 communicates at its opposite ends with the inlet 56 and the interior of the cup 57. A valve member 63 cooperates with the port 61 to control the admission of fuel to the cup 57 and the main reservoir 59. The valve member 63 is guided for reciprocation in the casing 60 and is movable by a lever 64 journaled on a shaft supported in the side walls of the chamber 54. Within the main 71

reservoir 59 there is a constant level float 65 which is secured to the lever 64 and which actuates the valve 63 to maintain a constant level of liquid fuel in the reservoir 59. The overflow edge 58 of the cup 57 is preferably above the normal constant liquid level in the reservoir 59 so that any air or gas entrained with the fuel and entering the cup 57 will be separated from the fuel at edge 58 and be released into the space in the chamber 54 above the surface of the fuel and not be carried therewith to the main nozzle. An air inlet 66, see Figs. 2 and 3, is formed in the top edge of the side wall of the chamber 54 to admit air at atmospheric pressure to the surface of the liquid fuel in the reservoir 59. The open top of the chamber 54 is closed by a cover member or plate 67 which is secured in position by screws, or the like, 68. Liquid fuel is supplied to the dash-pot chamber 29 and to the nozzle 36 from the reservoir 59 through a conduit 69 having its inlet portion formed by a tube 70 which extends downward into the reservoir 59 between the float 65 and the wall 55. The tube 70 extends through an aperture 71 in the cover member 67 and is screw-threaded, as at 72, or otherwise secured at its upper end in an external, longitudinally extending, tubular portion or boss 73, preferably formed integral with the die cast inlet member 2. The conduit 69 extends vertically upward into the boss 73 to a point in line with one of the supporting members 18. At this point, the conduit 69 is inclined upward and extends, as at 74, through the boss 73, the side wall of member 2, and longitudinally through one of the supporting members 18 into the bore of casing 17 between the plug member 19 and the piston 30.

Supported externally by the side wall of the chamber 54 and preferably formed integral therewith, there is a vertically extending, elongated housing or casing 75. The housing 75 is hollow, having a substantially cylindrical bore closed at its bottom end and open at its upper end, the lower portion of the bore defining a pump chamber 76 and the upper portion of the bore comprising a valve chamber 77. The bottom end portion of the pump chamber 76 is of reduced internal diameter, as at 78, to receive an annular valve seat member 79 with which a disc check valve 80 cooperates. The seat member 79 is held in position by a spider 81 which also serves to limit upward movement of the valve disc 80 away from its seat. The reduced chamber portion 78 communicates through a port 82 with a sump 83 in the bottom of the main reservoir 59. The sump 83 is formed in a boss 84 projecting from the bottom wall of the chamber 54 and is provided with a drain plug 85. Within the chamber 76 there is a pump plunger or piston 86 which is normally urged upward into engagement with its operating member or piston rod 87 by a helical coil spring 88 positioned in the chamber 76 and held under compression between the bottom wall of the chamber 76 and the piston 86. The operating member 87 has a free sliding fit within the vertical bore of a valve member 89 rotatably supported in the valve chamber 77. The valve member 89 projects upward out of the housing 75 and through an aperture 90 in the cover member 67. The aperture 90 is preferably in the form of a slot opening through the side edge of the member 67, as at 91, adjacent the mixing chamber member 3. The valve member 89 is provided with a circumferential groove 92 to receive the marginal edge of the member 67 surrounding the aperture 90 so that the valve member 89 is sup-

ported by the cover member 67 and held thereby against vertical movement although freely rotatable in the aperture 90 and the chamber 77. Within the bore 93 of the valve member 89 the operating member 87 is provided with oppositely positioned, longitudinally extending recesses 94, 95. The recesses 94, 95 are in communication with each other through transverse ports 96 in the member 87 and together provide a fluid chamber. The longitudinally extending recesses 94, 95 are preferably formed by removing opposite segmental portions of the surface of the member 87 such that the oppositely directed adjacent bases of the recesses 94, 95 which are joined by the vertically spaced ports 96 are substantially parallel to each other. The fluid chamber is in communication with the pump chamber 76 by a conduit 97 comprising a central port 98 through the piston 86 and a vertical bore extending upward into the member 87 from its lower end, the bore terminating at its upper end in a transverse port 99 opening into the recess 94. The pump chamber 76 is also in communication with the main reservoir 59 by means of ports 99^a and 99^b through the wall separating the chamber and reservoir, Fig. 3, the ports preferably inclining upward from the pump chamber into the reservoir. The normal liquid level designated by the line L—L is above the plane of piston 86 when in its uppermost position, so that the lower end portion of conduit or passageway 97 including port 98 will at all times contain liquid fuel. When the engine is hot, the liquid fuel in chamber 76 will vaporize forming gas bubbles which if port 99^a were not provided would discharge upward through conduit 97 forcing the fuel therein upward into the fluid chamber. This action which is percolation would be continuous as long as the engine was hot enough to vaporize the fuel in the pump chamber. In addition to the bubbles formed within chamber 76, some bubbles may also be entrained in the entering fuel. The liquid fuel discharged into the fluid chamber by this percolation when the engine is at rest would drain into the main mixture passageway through the pump discharge jet to be described and would pocket or trap in the inlet manifold positioned as is usual in downdraft carburetion beneath the carburetor. This trapped fuel would then prevent engine starting as the mixture supplied to the hot engine would be too rich to fire. This difficulty has been overcome by the provision of the vent port 99^a which opens into the chamber 76 at a point substantially in line with the plane of the bottom face of the piston 86 when the piston is in its uppermost position so that any gas bubbles entrained with fuel entering chamber 76 or formed by vaporization of the liquid fuel in chamber 76 will escape into the reservoir 59 and not force fuel through conduit 97 into the fluid chamber and thence into the manifold. Although the conduit 97 is normally open, it has been found that the bubbles will leave the chamber 76 via the port 99^a instead of through the conduit 97, evidently due to less resistance to escape of the bubbles via port 99^a. The piston has an upward projecting circumferential flange 99^c which serves to close the port 99^a when the piston is depressed, but even so some fuel will pass upward around the sides of the piston when it is operated. This fuel, if trapped above the piston, would prevent proper operation of the pump, so that the port 99^b is provided to permit discharge into the reservoir 59 on the suction stroke of the pump of any fuel which collects thereabove. The fluid chamber is 75

adapted to discharge fuel from the chamber 76 into the mixing chamber 6 through the bore of a nozzle or jet tube 100 which fits tightly as by screw-threaded engagement within the end of a passage 101 communicating at its outer end with the valve chamber bore 77. The valve member 89 is provided with a port 102 which normally registers with the outer end of the passage 101 to establish communication between the chamber 76 and the mixing chamber 6 but which is movable out of registry with passage 101 upon rotation of the valve member 89. The valve member 89 is also provided with a port 103 normally out of registry with the passage 101 but which is so positioned relative thereto, see Figs. 6 and 8, that it comes into registry with the passage 101 as the port 102 passes out of registry therewith upon rotation of the valve member 89. The housing 75 also includes a combined air inlet and fuel over-flow cup or chamber 104 positioned at the side of the valve chamber 77 and having a wall common to the wall of reservoir 54. The cup or chamber 104 is open to atmosphere by means of a passageway 105 leading into the reservoir chamber 59 above the liquid level therein and formed in the top face of the common side wall of the chambers 54 and 104. The passageway 105, which is preferably in the form of an open channel, has its top closed by the cover member 67. The common wall between the valve chamber 77 and the cup 104 is provided with upper and lower ports 106, 107 respectively which establish communication between the chamber and the top and bottom of the cup 104. The fluid chamber recess 95 is normally open to atmosphere from the reservoir 59 via cup 104 through a port 108 in the valve member 89 which registers with the port 106 when the fuel port 102 is in registry with the passage 101. The ports 106 and 108 are of sufficient size so that when they are in full registry the rate of admission of air to the fluid chamber will be sufficient to satisfy the mixing chamber suction on the nozzle 100, thereby preventing the suction from drawing fuel through the nozzle 100 from the chamber 76. In the horizontal plane of port 108, the valve member 89 has a plurality of additional ports 108^a, 108^b and 108^c which are of successively decreasing diameters and registerable with port 106. The fuel ports or jets 102, 103 are so positioned relative to each other and to passage 101 and to ports 108, 108^a and 108^b, and the ports 108, 108^a and 108^b are so positioned relative to air inlet port 106 that as the valve member 89 is rotated clockwise of Fig. 8 to close port 102 and open port 103, the air port 108^a will register with port 106. Port 108^a cuts down the air admitted to the fluid chamber sufficiently so that the mixing chamber suction will be effective on conduit 97 and the nozzle 100 will discharge a fuel mixture into the mixing chamber. Continued clockwise rotation of member 89 will register port 108^b with port 106 thereby further decreasing the air supply to the fluid chamber and since port 103 is still in registry with passage 101, a richer fuel mixture will be fed to the mixing chamber 6 through nozzle 100. The lower port 107 is in registry with a port 109 adapted to establish communication between the cup 104 and the fluid chamber via recess 95 but the port 109 is normally closed by the operating member 87 which serves as a valve controlling the port 109. The operating member 87 also serves as a valve controlling the air inlet port 106, the length of the recess 95 being such that when the member 87 is moved downward to actuate the piston 86

and sufficiently to cut off or close the port 108 and therefore the port 106, the lower end of the recess 95 will be in communication with the port 109. The valve member 89 is also provided with another port 110 which is vertically and circumferentially offset from and preferably positioned in a plane above the ports 102, 103. The port 110 is adapted to register with a priming passage or duct 111 opening at one end into the valve chamber bore 77 and at its other end 112 discharging into the main passageway through the casing 1 and preferably into the outlet 7 on the posterior side of the throttle valve 48. The duct 111 extends substantially horizontally through a boss 113 projecting externally from the side wall of the member 3. At a point in the boss 113 the duct 111 turns downward and opens through the flange 11 into registry with a vertical continuation of the duct 111 formed in a vertical boss 114 projecting from the external wall of the throttle body 20 member 4. The position of the port 110 is such that it will not come into communication with the duct 111 until the fuel port 103 is moved out of communication with the passage 101 and the port 108^c is moved into communication with the air inlet 106.

The valve member 89 is provided with an operating member 115 preferably in the form of a flat plate having an aperture therethrough to receive the valve member and which rides upon the top 30 face of the cover member 67, being held in engagement therewith by a marginal overlying flange 116 on the valve member 89. The operating member 115 and the valve member 89 are preferably fixed against relative rotation by a lug 35 or ear 117 projecting upward from the operating member into a slot 118 in the flange 116. The operating member 115 is provided with radially projecting stop portions 119, 120 which cooperate with a stop member 121 projecting from the top 40 face of the cover member 67 and positioned between the stop portions 119, 120 to limit rotation of the valve member 89. The operating member 115 also serves to actuate a loading means 122 for the suction operated valve means 42. The 45 loading means 122 comprises a substantially U-shaped lever member having its arms extending upward from their connecting portion which is journaled in a bearing sleeve 123 extending through and secured in the side wall of the mixing chamber member 3 such that one of the arms 124 is positioned within the chamber 6 and is movable into engagement with one of the valve members 42 and the other arm 125 is positioned externally of the member 3. The arm 125 is 50 connected by a pull wire or link 126 to a lug or ear 127 rigid with the operating member 115 and projecting upward therefrom adjacent the stop member 119. The link 126 preferably includes a coil spring 128 which transmits movement from member 115 to arm 124 so that the valve means 42 can move toward open position against the resilient force exerted by the loading means without changing the setting of the operating member 115. The relation of the loading means to the port 103 is preferably such that when the valve member 89 is rotated to bring the port 103 into registry with the passage 101 the arm 124 will be moved sufficiently to engage valve means 42 when closed without placing any 55 appreciable tension on the spring 128. In this position of the operating member 115 and loading means 122, the resistance afforded by the dashpot and spring 35 to opening movement of the valve means 42 will be increased by the resilient 60 force of the spring 128.

force of the spring 128. If the valve member 89 is rotated further in the same direction to bring the port 110 into registry with the duct 111, then the spring 128 will be elongated and placed under tension to resiliently urge the arm 124 against the valve means 42 when in closed position so as to materially increase the load on the valve members 42 exerted by the dash-pot and the spring 35. The operating member 115 and the parts actuated thereby are preferably held in their various positions of adjustment by a spring-pressed dog or detent 129 carried by the casing 75 at the side of the cup 104. The detent 129 is guided for reciprocation in a vertical bore 130 and extends upward through an aperture in the cover member 67 into engagement with the underside of the operating member 115 for co-operation with a plurality of circumferentially spaced, shallow recesses 131 formed in the underside of the operating member 115. The recesses 131 are preferably so positioned that the valve member 89 will be positively positioned for registry of the valve ports with their respective passages. The operating member 115 is also provided with a laterally extending cam portion 132 which projects outward beyond the casing 75 and is provided on its underside with an inclined cam face 133, for a purpose to be described. The throttle operating lever 50 is connected to the operating member 87 which extends above the valve member 89 by a substantially S-shaped thrust member or link 134 having one end extending into a slot 135 in the lever 50 and secured therein by a pivot pin 136. The other end of the member 134 extends into a vertical slot 137 in the top end of the operating member 87 and is pivotally secured therein and thereto by a pivot pin 138. Projecting from the thrust member 134 toward the casing 75, there is an arm or bracket 139 which terminates at its free end beneath the cam portion 132. The free end portion of the arm 139 is of substantially inverted U-shaped form, see Fig. 3. Through the horizontal portion 140 of the arm 139, there is adjustably screwed a cam follower screw 141 which projects upward into cooperable relation with the inclined cam face 133. A locking screw 142 threaded through the arms of the U-shaped bracket portion serves to clamp the cam follower 141 rigidly in adjusted position. The length of the cam face 133 is such that the follower member 141 will engage the horizontal under face 143 of projecting portion 132 when the port 103 is brought into registry with the passage 101, thereby limiting further opening movement of the throttle valve 48 upon continued rotation of the operating member 115. Beyond the horizontal face 143 the underside of the projecting portion 132 is relieved, as at 144, to provide a cam face 60 vertically offset from and above the plane of the face 143. When the operating member 115 is rotated sufficiently to bring the port 110 into registry with the duct 111, the follower member 141 will move from the face 143 onto the face 144 so as to permit upward movement of the thrust member 134 and movement of the throttle valve 48 toward closed position. The operating member 115 is preferably provided with an operating arm or lever 145 which may be connected by suitable linkage to a remote point such as the dash of the automobile.

The operation of my carburetor, assuming the same to have been connected at the outlet 7 to the manifold of an internal combustion engine and the fuel inlet 56 to have been con-

nected to a suitable source of fuel supply, is as follows: Prior to starting or cranking the engine, if the engine is cold the operating member 115 will be rotated clockwise of Fig. 2 from the position shown until the stop 119 engages the stop member 121. This operation will move the primer port 110 into full registry with the primer duct or passage 111, will carry the fuel ports 102 and 103 beyond the passage 101, and will also bring the small air inlet port 108^c into registry with the air inlet port 106. In addition to establishing direct communication between the primer duct outlet 112 and the main reservoir 59 via the pump chamber 76, the rotation of the valve member 89 will actuate the loading means 122 to provide a maximum load on the air inlet valve members 42. The rotation of the operating member 115 will also move the thrust member 134 downward by engagement of the cam face 133 with its follower 141, thereby moving the throttle valve 48 toward open position sufficiently so that stalling of the engine will be prevented. It will be noted that the complete movement of the operating member 115 to bring the port 110 into registry with the duct 111 will move the throttle valve first to a predetermined open position by operation of cam face 133, then as the follower member 141 leaves the cam face 143 and moves upward into engagement with the face 144, the throttle valve will move from this predetermined open position toward closed position but not sufficiently to engage stops 51 and 52. With the ignition turned on, if the engine is now cranked liquid fuel will be drawn through the duct 111 together with a very small quantity of air admitted by bleed port 108^c to mix with such air as can pass the additionally loaded valve members 42 through the annular aperture 47 and the slightly cracked throttle valve to provide a mixture which is exceedingly rich in fuel and desirable for cold engine starting. The bleed port 108^c serves primarily to decrease the weight of the liquid fuel column to aid in lifting the fuel from chamber 76 to outlet 7 without materially affecting the fuel mixture ratio. As soon as the engine fires and is operating under its own power, the operator will move the operating member 115 counterclockwise of Fig. 2 to cut down the richness of the fuel mixture, except in unusually extreme cold weather operation. In normal cold engine operation, the member 115 is returned to a position which will cut off the port 110 from the duct 111 and bring the warming-up jet or port 103 into registry with the passage 101. The air inlet port 108^b will now be in registry with air inlet port 106 so that a supplemental fuel mixture will be supplied to chamber 6 through nozzle 100. This return movement of the operating member 115 will move the cam face 143 into engagement with the follower 141, thereby depressing the thrust member 134 and moving the throttle valve to a further open position such as is required to maintain idling operation of the engine during the warming-up period. The port 103 is preferably of smaller diameter than the port 110 and the air port 108^b is larger than the port 108^c so that the richness of the supplemental fuel supplied to the mixing chamber by nozzle 100 will be decreased. This return movement of the operating member 115 will also partly relieve the increased tension of the loading means 122 against the valve members 42 while, however, maintaining a greater resistance to opening movement of the valve members 42 than is normally exerted by the dash-pot and the spring 35. If 75

the throttle valve 48 is now opened to increase the speed of the engine, the ratio of fuel to air supplied from the main nozzle 36 and the main air inlet 5 will be increased over the ratio of fuel to air normally supplied by the main fuel and air inlets when the loading means 122 is ineffective. As the engine warms up, the operating member 115 will be returned further in a counter-clockwise direction thereby bringing air port 108 into registry with port 106 while maintaining the fuel port 103 in registry with nozzle passage 101 and cam face 143 in engagement with the follower 141. This will only change the mixture ratio of the supplemental fuel supply discharged by nozzle 100, that is, the ratio of air to fuel in the supplemental mixture will be increased. As the operating member 115 is moved to normal operating position, the fuel port 102 will move into full registry with the passage 101 and the air inlet port 108 will be moved into registry with the air inlet port 106 so that the fluid chamber comprising recesses 94 and 95 will be under substantially atmospheric pressure. As the air inlet ports 106 and 108 are of sufficient size to maintain air at substantially atmospheric pressure in the fluid chamber, fuel will not be drawn from the pump chamber 76 as the suction on the nozzle 100 will be satisfied by the air supplied to the fluid chamber. The movement of the operating member 115 to normal position, Fig. 2, will also act through the link 126 to move the loading means 122 to inactive position, as shown in Fig. 4, with the result that the valve members 42 are resisted on opening movement solely by the dash-pot piston 30 and the spring 35. This movement of the operating member 115 to normal position when stop 120 engages stop member 121 will also permit cam follower member 141 to move up along the cam face 133 until the cam face 133 no longer bears against the follower member 141, thereby permitting the throttle valve 48 to return to substantially closed, normal idling position with stop member 51 engaging stop 52. If the throttle is gradually moved toward open position, the suction transmitted to the mixing chamber 8 will increase and cause the valve members 42 to move away from each other about their supporting shaft 40 and toward open position. As the valve members 42 open, they will act through the operating members 43 and the nozzle sleeve 31 to move the dash-pot piston 30 and its port 32 relative to the metering valve 28 to increase the annular fuel orifice at the entrance to the stem bore 32. This interconnection between the fuel metering means and the air metering means results in an increase of the fuel supplied by the main nozzle to the mixing chamber as the air admitted to the mixing chamber from the air inlet 5 is increased so as to maintain a desirable ratio of fuel to air during certain periods of engine operation. As the throttle moves toward open position, it will act through the thrust member 134 upon the operating member 87 and move the same downward in the bore 93. As the member 87 moves downward, the top end edge of the recess 95 will move across the air inlet port 108, and when the member 87 has decreased the air admitted to the fluid chamber from port 108 below the suction demand on the nozzle 100, then fuel will be drawn from the pump chamber 76 upward through the conduit 97 into the fluid chamber recess 94 to mix therein with the small quantity of air still admitted at port 108 and will discharge as a mixture through the port 102 and the nozzle 100 into the mixing chamber to increase the ratio of fuel to air supplied to the engine as the power demand increases. Further downward movement of the operating member 87 will cut off the air inlet port 108 but simultaneously therewith the bottom lower edge of the recess 95 will uncover the port 109 so that air admitted to the cup 104 via passage 105 from the main fuel reservoir 59 will enter the fluid chamber, but the air admitted through the port 109 which is of smaller diameter than the port 108 will be insufficient to satisfy the mixing chamber suction on the nozzle 100 so that a supplemental supply of fuel from pump chamber 76 and air from port 109 will continue to discharge into the mixing chamber through the nozzle 100 as the opening movement of the throttle continues. If the throttle valve is opened quickly from substantially closed or normal running position but not far enough to uncover the port 109, there will be a momentary increase in the supply of fuel supplied to the mixing chamber to supplement the discharge from the main nozzle. This momentary supplemental discharge will be forced from the pump chamber 76 upward through the port 98 and conduit 97 into the fluid chamber recess 94 and will be forced through the nozzle 100 by the atmospheric air over the surface thereof which enters the fluid chamber through the air inlet ports 106 and 108. As soon as the fuel displaced from the pump chamber has been forced out through the nozzle 100, further discharge of fuel from the nozzle 100 will cease as the suction in the mixing chamber will again be satisfied by the air entering the fluid chamber through port 108. If the throttle valve 48 is moved quickly to full open position or sufficiently open so that port 109 is uncovered, then there will be a discharge of solid liquid fuel from the pump chamber 76 through the conduit 97, port 102 and the nozzle 100 into the mixing chamber as above described for part throttle acceleration. In this latter case, however, fuel entering the fluid chamber will overflow through ports 108 and 106 into the cup 104 prior to the cut-off of the port 108 by the operating member 87. This fuel in cup 104 will be under atmospheric pressure from the reservoir 59 via passage 105 so that when the member 87 is depressed sufficiently to bring recess 95 into registry with port 109, the liquid fuel in cup 104 will be discharged through aligned ports 107 and 109 into the fluid chamber recess 95, and thence through the lower port 96 into recess 94 for discharge through the nozzle 100 into the mixing chamber. It may be noted that the fuel in cup 104 will not be discharged therefrom during the discharge stroke of the piston 30 but will follow after the forced discharge from the pump. When the pump stroke has been completed, the liquid fuel in cup 104 will be discharged by the atmospheric air over the surface thereof into the fluid chamber through port 109 which will supplement the supplemental supply of fuel drawn by mixing chamber suction on nozzle 100 through conduit 97 from the pump chamber. When cup 104 is emptied of fuel, the port 109 will be open to atmosphere but its size is insufficient to satisfy the suction on the nozzle 100 so that the forced discharge of fuel through nozzle 100 by the pump will be followed by fuel sucked from the chamber 76 together with some air from port 109. This additional supply of fuel from chamber 76 and air from inlet port 109 which follows the pump discharge acts to supplement the main mixture supply of fuel from the main nozzle 36 and air from inlet 5 to create the necessary mixture.

sary rich mixture for high power demands of the engine. It will be noted that the supplemental supply of fuel following the pump discharge stroke decreases gradually in the ratio of fuel to air, 5 the supplemental supply being first solid liquid fuel from chamber 76 and cup 104, then fuel from chamber 76 mixed with air and fuel from cup 104, and finally fuel from chamber 76 and air alone from cup 104 as the fuel supply is exhausted from the cup 104 thereby preventing uneven engine operation following pump discharge. The check valve 80 serves to prevent the return of fuel from the pump chamber to the main reservoir 59 during the discharge stroke of the piston 86 but opens on upward movement of the piston to replenish the chamber 76. The spring 88 not only holds the piston 86 in engagement with the lower end of the operating member 87 as the operating member 87 is moved upward but 10 also acts through the thrust member 134 to urge the throttle valve toward closed position. The pump is operable to discharge fuel into the main mixture passage irrespective of the position of the operating member 115. If the primer port 110 is in registry with passage 111, opening of the throttle valve will act on piston 86 to force solid liquid fuel through the jet 112 into the outlet 7. When the warming-up port 103 is in communication with the passage 101, the operation 15 of the pump will be as above described in connection with discharge through the port 102, except that the lower discharge port 107 from cup 104 will be closed so that any liquid fuel trapped in cup 104 will not pass to nozzle 100 upon completion of the pump stroke, the port 109 being 20 out of registry with port 107. This omission of the fuel feed from cup 104 is compensated by the richer follow up mixture fed to nozzle 100 due to the fact that air ports 108^a and 108^b admit 25 less air to the fluid chamber than does the port 109.

What I claim and desire to secure by Letters Patent of the United States is:

45 1. A carburetor comprising a hollow casing having a substantially straight vertical open-ended passageway therethrough, one end portion of said passageway defining an air inlet converging in the direction of flow, the other end portion of said passageway defining a mixture outlet, a
50 dash-pot casing concentrically positioned in said air inlet in circumferentially spaced relation to the converging walls of said passageway, supporting members bridging said air inlet and extending between said casings and rigidly supporting
55 said dash-pot casing, the inner end of said dash-pot casing being open and having a hollow extension providing guide means, a piston in said dash-pot casing having a hollow stem opening through said piston and reciprocably supported
60 in said extension, a hollow plug member closing the outer open end of said dash-pot casing, a fuel metering valve adjustably supported in the bore of said plug member and extending into the bore
65 of said stem to regulate flow therethrough, a fuel reservoir, a fuel supply conduit extending from said reservoir and opening longitudinally through one of said supporting members into said dash-pot casing between said piston and said plug member, suction operated valve means controlling air flow through said passageway, said stem having a nozzle member discharging into said passageway on the outlet side of said valve means, means operatively connecting said valve means and said nozzle member whereby said piston opposes movement of said valve means by suction,
70
75

and means to control discharge from the outlet end of said passageway.

2. A downdraft carburetor comprising a throttle body member, a mixing chamber member mounted on and secured to said throttle body member, an air inlet member mounted on and secured to said chamber member, said members being hollow and combining to provide an open-ended passageway, a throttle valve journaled in said throttle body member, downward converging air valve members pivotally supported in said passageway adjacent the side walls thereof and meeting each other to close said passageway, a housing member rigidly supported in said air inlet member and containing a dash-pot chamber, a piston in said dash-pot chamber, said valve members having an aperture therethrough, a nozzle tube connected to said piston and projecting from said housing member into said aperture, means operatively connecting said valve members and said tube for movement in unison, a metering valve extending into the bore of said tube to meter flow therethrough, a fuel reservoir rigidly carried by said mixing chamber member and positioned at one side of said throttle body member, and a fuel supply conduit leading upward from said reservoir to said housing member to feed fuel to said nozzle tube. 25

3. A carburetor comprising a hollow casing having a passageway therethrough, main air and fuel inlets discharging into said passageway, a fuel reservoir supplying said fuel inlet, a supplemental fuel supply conduit leading from said reservoir to said passageway, a valve controlling flow through said conduit, a plate member carried by said valve and movable therewith, a cam member on said plate member, a throttle valve controlling flow through said passageway and having a shaft journaled in said casing, an operating arm fixed on said shaft, a thrust member guided for reciprocation and operatively connected to said arm, and a cam follower member carried by said thrust member and cooperable with said cam member whereby movement of said supplemental supply valve will actuate said throttle valve. 45

4. A carburetor comprising a hollow casing having a passageway therethrough, main air and fuel inlets discharging into said passageway, a fuel reservoir supplying said fuel inlet, a supplemental fuel supply conduit leading from said reservoir to said passageway, a valve controlling flow through said conduit, a plate member carried by said valve and movable therewith, a cam member on said plate member, a throttle valve controlling flow through said passageway and having a shaft journaled in said casing, an operating arm fixed on said shaft, a fuel pump discharging into said passageway, a thrust member operatively connecting said throttle valve and said pump, and a cam follower member carried by said thrust member and cooperable with said cam member whereby movement of said supplemental supply valve will actuate said throttle valve. 50 55 60 65

5. A carburetor comprising a hollow casing having a passageway therethrough, main air and fuel inlets discharging into said passageway, a fuel reservoir supplying said fuel inlet, a throttle valve controlling the discharge from said passageway and having a shaft journaled in said casing, an operating arm fixed on said shaft, a valve housing carried by said casing, a conduit leading from said reservoir to said housing, a conduit leading from said housing to said pas- 70 75

sageway on the inlet side of said throttle valve, a conduit leading from said housing to said passageway on the outlet side of said throttle valve, a valve member in said housing having an operating member external of said housing, said valve member controlling communication between said first-named conduit and said second-named conduit and between said first-named conduit and said third-named conduit, a cam member movable by said operating member, a thrust member guided for reciprocation and operatively connected to said throttle arm, and a cam follower member fixed on said thrust member and cooperable with said cam member whereby movement of said valve member will actuate said throttle valve.

6. A carburetor comprising a hollow casing having a passageway therethrough, main air and fuel inlets discharging into said passageway, a fuel reservoir supplying said fuel inlet, a throttle valve controlling the discharge from said passageway and having a shaft journaled in said casing, an operating arm fixed on said shaft, a valve housing carried by said casing, a conduit leading from said reservoir to said housing, a conduit leading from said housing to said passageway on the inlet side of said throttle valve, a conduit leading from said housing to said passageway on the outlet side of said throttle valve, a valve member in said housing having an operating member external of said housing, said valve member controlling communication between said first-named conduit and said second-named conduit and between said first-named conduit and said third-named conduit, a cam member movable by said operating member, a thrust member guided for reciprocation and operatively connected to said throttle arm, a cam follower member fixed on said thrust member and cooperable with said cam member whereby movement of said valve member will actuate said throttle valve, suction operated valve means controlling said air inlet, and means actuated by said valve member for resisting operation of said valve means by suction.

7. A carburetor comprising a hollow body member having a passageway therethrough, main air and fuel inlets to said passageway, a fuel reservoir, a conduit leading from said reservoir to said fuel inlet, a valve casing having a substantially cylindrical bore, a supplemental fuel supply conduit leading from said bore and discharging into said passageway, a rotatable valve member in said bore and having a port registerable with said supplemental conduit, means to supply fuel from said reservoir to said valve casing and port, a cover member for said reservoir, said cover member having means supporting said valve member in operative position in said valve casing, and operating means to rotate said valve member.

8. A carburetor comprising a hollow body member having a passageway therethrough, main air and fuel inlets to said passageway, a fuel reservoir, a conduit leading from said reservoir to said fuel inlet, a valve casing having a substantially cylindrical bore, a supplemental fuel supply conduit leading from said bore and discharging into said passageway, a rotatable valve member in said bore and having a port registerable with said supplemental conduit, means to supply fuel from said reservoir to said valve casing and port, a cover member for said reservoir, said cover member having means supporting said valve member in operative position in said valve casing, operating means to rotate said valve member,

and means cooperable with said operating means to hold said port in registry with said supplemental conduit.

9. A carburetor comprising a hollow body member having a passageway therethrough, main air and fuel inlets to said passageway, a fuel reservoir supported by said member, a conduit leading from said reservoir to said fuel inlet, a pump housing positioned externally of and mounted on said reservoir and having a pump chamber, a piston reciprocable in said chamber, a fuel discharge conduit leading from said chamber to said passageway, an air inlet to said discharge conduit from said reservoir above the normal liquid level therein, a pump rod engaging said piston, means operable by said rod to close said second-named air inlet, a throttle valve controlling flow through said passageway, and means operatively connecting said throttle valve and said pump rod.

10. A carburetor comprising a hollow body member having a passageway therethrough, main air and fuel inlets to said passageway, a fuel reservoir supported by said member, a conduit leading from said reservoir to said fuel inlet, a pump housing positioned externally of and mounted on said reservoir and having a pump chamber, a piston reciprocable in said chamber, a fuel discharge conduit leading from said chamber to said passageway, an air inlet to said discharge conduit from said reservoir above the normal liquid level therein, a pump rod engaging said piston, means operable by said rod to close said second-named air inlet, a throttle valve having a shaft and controlling flow through said passageway, an operating arm fixed on said shaft, and a thrust member having its opposite ends pivotally connected to said arm and to said pump rod.

11. A carburetor comprising a hollow body member having a passageway therethrough, main air and fuel inlets to said passageway, a fuel reservoir positioned at one side of and supported by said body member, a conduit leading from said reservoir to said fuel inlet, a housing member positioned at one side of and supported by said reservoir, said housing member having a vertical cylindrical bore with its upper portion defining a valve chamber and its lower portion defining a pump chamber, a fuel supply conduit leading from said reservoir to said pump chamber, a hollow valve member rotatable in said valve chamber and having a vertical bore therethrough, a piston in said pump chamber, a pump rod extending through and slidably fitting in the bore of said valve member and cooperating with said piston, a combined air and fuel overflow chamber at the side of said valve chamber, said overflow chamber having an air inlet port from said reservoir and having an air outlet port communicating with said valve chamber, said overflow chamber having a discharge port at its lower end communicating with said valve chamber, said valve member having ports registerable respectively with said air outlet and discharge ports respectively, a discharge conduit leading from said pump chamber to the bore of said valve member, a supplemental fuel supply nozzle discharging into said passageway and communicating with said valve chamber, said valve member having a port to supply fuel to said nozzle, supplemental fuel supply means discharging into said passageway and communicating with said valve chamber, said valve member having a port for supplying fuel to said supplemental means when said valve member is actuated to cut off fuel to said nozzle, said pump rod having means to close said

- overflow chamber air outlet port, said pump rod having means operable when said air outlet port is closed to establish communication between said overflow chamber discharge port and said nozzle, 5 a throttle valve controlling discharge from said passageway, means operable upon operation of said valve member to move said throttle valve toward open position, suction operated valve means controlling said air inlet, and means operable 10 upon operation of said valve member to resist opening movement of said valve means.
12. A carburetor comprising a hollow body member having a passageway therethrough, main air and fuel inlets to said passageway, a fuel 15 reservoir, a conduit connecting said reservoir and said fuel inlet, a pump chamber having fuel supply means, a discharge conduit extending upward from said chamber and discharging into said passageway, a piston in said chamber, and venting means opening into said chamber through a side wall thereof beneath said piston whereby liquid fuel will not be forced upward through said conduit by gas bubbles formed within or entering said chamber.
13. A carburetor comprising a hollow body member having a passageway therethrough, main air and fuel inlets to said passageway, a fuel reservoir, a conduit connecting said reservoir and said fuel inlet, a pump chamber having fuel supply means, a discharge conduit from said chamber to said passageway, and a piston in said chamber, said reservoir having a port communicating with the upper end of said chamber beneath said piston whereby to relieve said chamber of vaporized gas.
14. A downdraft carburetor comprising a hollow body member having a passageway therethrough, a fuel supply conduit discharging into said passageway, a dash-pot chamber in said conduit having a piston provided with a valve port, said piston having a hollow stem communicating with said port and defining a fuel nozzle, a metering valve cooperable with said port, valve means controlling air flow through said passageway and operatively connected to said stem, and a bleed port through said stem adjacent said piston establishing communication between the top of said chamber and the bore of said stem whereby fuel vapor or gas bubbles formed in said chamber can by-pass said valve port.
15. A carburetor comprising a hollow body member having a passageway therethrough, main air and fuel inlets to said passageway, a fuel reservoir supported by said body member, a conduit leading from said reservoir to said fuel inlet, a housing member supported by said reservoir, said housing member having a vertical cylindrical bore with its upper portion defining a valve chamber and its lower portion defining a pump chamber, means to supply fuel from said reservoir to said pump chamber, a hollow valve member rotatable in said valve chamber and having a vertical bore therethrough, a piston in said pump chamber, a pump rod extending through the bore of said valve member and cooperating with said piston, a combined air and fuel overflow chamber at the side of said valve chamber, said overflow chamber having an air inlet port and having an air outlet port communicating with said valve chamber, said overflow chamber having a discharge port at its lower end communicating with said valve chamber, said valve member having ports registerable respectively with said air outlet and discharge ports respectively, a discharge conduit leading from said pump chamber to the bore of said valve member, supplemental fuel supply means discharging into said passageway and communicating with said valve chamber, said valve member having a port for supplying fuel to said supplemental means, said pump rod having means to close said overflow chamber air outlet port, said pump rod having means operable when said air outlet port is closed to establish communication between said overflow chamber discharge port and said nozzle, and a throttle valve controlling discharge from said passageway.
16. A carburetor comprising a hollow body member having a passageway therethrough, main air and fuel inlets to said passageway, a fuel reservoir supported by said body member, a conduit leading from said reservoir to said fuel inlet, a housing member supported by said reservoir, said housing member having a vertical cylindrical bore with its upper portion defining a valve chamber and its lower portion defining a pump chamber, means to supply fuel from said reservoir to said pump chamber, a hollow valve member rotatable in said valve chamber and having a vertical bore therethrough, a piston in said pump chamber, a pump rod extending through the bore of said valve member and cooperating with said piston, a combined air and fuel overflow chamber at the side of said valve chamber, said overflow chamber having an air inlet port and having an air outlet port communicating with said valve chamber, said overflow chamber having a discharge port at its lower end communicating with said valve chamber, said valve member having ports registerable respectively with said air outlet and discharge ports respectively, a discharge conduit leading from said pump chamber to the bore of said valve member, supplemental fuel supply means discharging into said passageway and communicating with said valve chamber, said valve member having a port for supplying fuel to said supplemental means, said pump rod having means to close said overflow chamber air outlet port, said pump rod having means operable when said air outlet port is closed to establish communication between said overflow chamber discharge port and said nozzle, and a throttle valve controlling discharge from said passageway.
17. A carburetor comprising a throttle body member, a mixing chamber member and an air inlet member, said members being separable from each other and being rigidly secured together to provide an open-ended passageway, means controlling admission of air from said air inlet member to said throttle body member, a fuel nozzle discharging centrally into said mixing chamber member and on the outlet side of said control means, a fuel reservoir carried by and positioned laterally of said mixing chamber member and forming therewith a unit, a cover member for said reservoir having an opening therethrough, an external boss carried by and extending longitudinally of said air inlet member and overlying said opening, said boss having an open-ended conduit therethrough communicating at one end with said nozzle, and a fuel inlet tube in said opening and extending from said boss into said reservoir and discharging into the other end of said open-ended conduit.
